AUTOMATIC CURRENT LIMITING DEVICE
FOR USE IN ELECTRICAL SIGNALING

Gaston Adelin Mathieu, London, England, assignor to Radio Corporation of America, a corporation of Delaware

Application May 11, 1929, Serial No. 362,266
In Great Britain May 22, 1928

12 Claims. (Cl. 250—20)

This invention is for improvements in or modifications of the invention set forth in U. S. application No. 239,843, filed Dec. 14, 1927, which resulted in U. S. Pat. #1,892,215, on Dec. 27, 1932, and relates to automatic limiting and regulating devices for use in electrical signaling. While not confined to its application thereto, the invention is especially suitable for limiting or regulating the intensity of signals transmitted over a land line 10 from the output side of a wireless or other telephone or telegraph receiver.

U. S. Patent No. 1,892,215 describes an automatic limiting and regulating device comprising in combination signal intensity reducing means and a plurality of relays energized by currents substantially proportional to the intensity of the signals to be limited and regulated and adapted to be actuated in succession by rising values of said intensity, so that the attenuation or weakening 15 properties of the said intensity reducing means are varied according to variations in the said signal intensity.

In one arrangement briefly described in the above referred to application in which the device was applied to a receiver comprising a high frequency amplifier and a detector, the said device being inserted to regulate the current from the detector (or from a low frequency amplifier following the detector) it was proposed to increase the range of regulation beyond that of the signal intensity reducing means by providing an additional relay adapted to be actuated if the signal strength rises above that necessary to actuate all the other control relays, and being arranged to switch out one or more stages of the high frequency amplifier.

The arrangement was preferably such that the switching out of the stage or stages of the high frequency amplifier caused the direct current to drop to such a value that all but the first of the other relays were de-actuated, the re-installation of the said stage or stages of high frequency amplification being secured automatically by associating with the relay switch winding co-operating with the first control relay an extra contact adapted to de-actuate the relay controlling the said stage or stages when the direct current strength had fallen sufficiently. In this way the range of control was nearly doubled.

The principal object of the present invention is to provide improved means for securing an increase of range of regulation, whereby said range may be increased to be more than twice the range of the signal intensity reducing means.

According to one modification of the present in-

vention, in an installation comprising an automatic current limiting and regulating device, inserted to limit or regulate low frequency currents, there is provided automatic means for regulating the input to the automatic regulating device in a plurality of steps, said means being so controlled that for each step of input strength the automatic current limiting and regulating device gives its own range of regulation, the steps being such that the whole effective range is substantially 10 continuous, i. e. broken only by the steps of regulation effected by the automatic current limiting and regulating device.

In a further modification of my invention the means for regulating the input to the detector are not actuated by relays in the automatic current limiting and regulating device but directly under the control of the output current from the said detector.

The invention is illustrated in the accompanying diagrammatic drawings, in which,

Figure 1 shows an arrangement in which the intensity of the signals impressed on the input elements of the amplifier stage is regulated, by means of relays actuated by current from the detector output;

Figure 1A is a line diagram of the arrangement of Figure 1;

Figure 2 shows an additional resistance network to be used with the modification shown in Figure 1;

Figure 2A is a line diagram of the arrangement of Figure 1 including the additional amplitude control means shown in Figure 2.

Figure 3 shows an arrangement in which the intensity of the signals impressed on the input elements of the amplifier are regulated directly by the output current from the detector;

Figure 3A is a line diagram illustrative of the apparatus shown in Figures 3 and 4; while

Figure 4 shows a modification of Figure 3 in which high speed relays are interposed between the detector output and the control apparatus.

Referring to Figure 1 of the specification drawings TR1 is an input transformer for a high frequency amplifier which is represented by two valves V1, V2, in push-pull connection, the output from which works into a detector DS shown in Fig. 1A in whose output circuit is incorporated an automatic regulating device in accordance 45 with the disclosure of U. S. Pat. No. 1,892,215. The secondary of the transformer is associated with resistances R1, R2 dimensioned in known manner to give proper terminal conditions to avoid reflection, and tapped as shown, the tap- 50 55

pings being connected to fixed contacts 5a—5e and 6a—6e respectively. Each set of fixed contacts is associated with a wipe brush 5g or 6g, the two brushes being keyed upon a common shaft S and being connected via contacts 5f and 6f to the grids of the valves V1 and V2 respectively. In this way the proportion of the signal strength in the transformer secondary, which is transferred to the valves V1, V2, and thus to the detector (not shown in Fig. 1) is caused to depend upon the position of the brushes 5g, 6g, which should be so dimensioned and arranged as never to break the circuits to the grids of the valves V1 and V2.

15 The shaft S is adapted to be rotated in the direction to reduce input strength by an electro-magnet M1, actuating a pawl 3a driving a ratchet wheel 3 fast upon the shaft S and in the other direction (i. e. to increase the strength) by a 20 similar magnet M2 operating through a pawl 4a and ratchet wheel 4. The pawls 3a, 4a are associated with springs Sp1, Sp2, adapted to bias them away from their respective ratchet wheels 3, 4.

25 The terminal 7 and corresponding earthed point 7a are associated with an auxiliary contact (not shown) provided upon the last relay switch S6 of Figure 2 of U. S. Patent No. 1,892,215 incorporated in the automatic current limiting and regulating device in such manner that when the 30 said relay closes a circuit is completed from terminal 7 to earth 7a. The terminal 8 and corresponding earthed point 8a are associated with an auxiliary contact (not shown) provided upon the first relay switch S1 of Figure 2 of the above 35 referred to patent incorporated in the automatic current limiting and regulating device, the arrangement being such that the points 8, 8a are connected together when the said relay opens. These connections between the current limiting relay RN and the control apparatus connected with R1 and R2 are shown diagrammatically in Figure 1A.

40 3b, 4b are normally closed contacts adapted to be opened through the forks 3c 4c respectively, 45 when the associated pawls 3a 4a are moved.

The function of the contacts 3b or 4b is to permit the spring Sp1 or Sp2 to return its associated pawl 3a or 4a to its initial position by opening circuiting one of the electro-magnets M2 or M1.

50 It will be seen that if the point 7 or 8 be connected to earth, by action of the switches S6 and S1, respectively, of Fig. 2 of U. S. Patent #1,892-215, the action of the electromagnet M1 or M2 and its associated spring Sp1 or Sp2, contact 3b or 4b, and fork 3c or 4c will be to rotate the shaft S progressively in one direction or the other, until a contact 1b or 2b, bearing upon a slip ring 1c or 2c contacts with an insulated segment 1d or 2d upon one of the slip rings when the circuit to the electromagnet M1 or M2 will be broken. The segments 1d and 2d should be so positioned as to prevent the shaft S from being rotated in either direction beyond the designed limits of movement for the brushes 5g, 6g.

65 In practice, the resistances R2 and R1, the wipe brushes 5g and 6g, and their associated contacts, may be arranged within a screening box for the high frequency amplifier, all the other mechanism, including the electromagnets, being arranged outside this box.

70 Further, in order to reduce induction from the electro-magnet windings M1 and M2, the said windings are preferably incorporated in a closed iron pot forming the armature of the electro-magnet.

The tappings upon the resistances R1, R2 should be such that when the signal strength is rising, each step of the brushes 5g 6g in a direction to reduce the signal input into the detector will cause all the relays, except the first one, incorporated in the automatic current limiting and regulating device, to open, while each step in a direction to increase the said input will cause all the said relays, except the last one, to close.

If these conditions be not fulfilled, it will be 10 apparent that since the first and last relays of the automatic current limiting and regulating device control the magnets M1 and M2, "hunting" or to and fro adjustment in the regulation of the high frequency input will result—an objectionable condition commonly met with in known regulating apparatus and giving rise to intermodulation, increase of noise level and distortion generally.

15 The operation of the apparatus shown in Figure 1 and the cooperation thereof with the amplitude 20 control network and the actuating relays disclosed in detail and claimed in United States application #239,843, December 14, 1927, will be better understood by reference to the line diagram of Figure 1A in which A is the aerial; R indicates the 25 receiver; RF indicates the high frequency amplifier which, in this instance, includes V1, V2 of Figure 1; DS is the detector; RN is the attenuation network and AF is the low frequency amplifier. The direct current component is taken from 30 direct current amplifier DCA and used to energize the control relays CR which control attenuation network RN. Up to this point the apparatus shown is substantially similar to the apparatus of 35 Figure 1 of the United States application referred to above. In the present case, however, CR, that is the control relays, are connected in a manner and for a purpose set forth more in detail above in connection with the discussion of Figure 1 to the high frequency amplifier RF through the magnetic and mechanical relay MR. The object of the last connection is to control the resistances R1 and R2 adapted to be inserted in the input 40 circuit of the radio frequency amplifier in accordance with the positions of the first and final 45 contact in the network resistance RN.

With the arrangement described, however, when the first relay in the automatic current limiting and regulating device operates, it causes operation 50 of the magnet M2 which actuates the brushes 5g 6g to increase the input into the high frequency amplifier to an amount such that all the relays, except the last, in the said automatic device operate, so that the same volume of low frequency output into the land-line or telephone 55 receiver is maintained by a simultaneous increase in the high frequency input and a compensating decrease in the low frequency input into the low frequency amplifier.

The fact that the change in the high frequency 60 amplification is secured by the action on one relay, while the compensation change on the low frequency side is obtained by the closing of a plurality, say, four relays, working in succession, necessarily involves two different transit times, 65 which causes a momentary overload of the low frequency amplifier.

This sudden and momentary throw out of balance in the correct input of the respective high frequency and low frequency amplifiers, produces 70 a kind of rushing noise in the telephone and, moreover, is apt to introduce a momentary paralysis of the low frequency amplifying valves.

Means should therefore be provided to avoid this defect. Such means may comprise an addi- 75

tional resistance network, introducing a loss of about 10 to 15 transmitting units into the input of the low frequency amplifier during the period due to the difference of time transit.

5 Figure 2 of the specification drawings illustrates diagrammatically one arrangement of this kind. Referring to the said Figure 2, O₁, O₂ represent the leads from the detector output, and L₁, L₂ the leads towards the output attenuating network regulating the output power into the low frequency land-line or telephone amplifier. R P is a resistance network, similar to and adapted to be momentarily added to the resistance network comprised in the automatic current limiting 10 and regulating device. The resistance R P is momentarily included in circuit by means of an auxiliary relay, comprising a winding W₁ and contacts 1, 2, 3, 4, the winding W₁ being connected in parallel with the winding of the electromagnet 15 M₂. It will be seen that when the first relay in the automatic current limiting and regulating device moves to actuate the magnet M₂, the extra resistance R P will be momentarily inserted 20 at the same time, as more input power is allowed into the high frequency amplifier.

25 By regulating the mechanical transit time of operation of the auxiliary relay (winding W₁) it is possible to obtain noiseless operation.

Figure 2A is a line diagram showing the connection between the apparatus shown in Figure 2 of the present invention and the attenuation network and control relays and so forth shown in detail in the parent application. This line diagram is similar in many respects to the line diagram of Figure 1A differing therefrom in that the additional resistance network of Figure 2 is shown connected between the detector and the attenuation network and controlled by current which controls the resistances R₁, R₂ arranged to be inserted in the radiofrequency amplifier RF by the action of the control relays CR. The purpose for the present arrangement is, as pointed out in detail above, to prevent overloading of the valves between the time when the change in resistance in R_N is caused by the control relay and the time at which the change of resistance in the input circuit of the radiofrequency amplifier has been effected.

50 The modification shown in Figure 3 of the accompanying drawings differs from the previously described arrangements mainly in that the means for regulating the input to the detector are not actuated by relays in the automatic current limiting and regulating device but directly under the control of the output current from the said detector. In Figure 3 of the accompanying drawings, parts which correspond to parts shown in Figure 1 of the drawings are indicated by like references.

60 Referring to Figure 3 of the accompanying drawings, it will be noted that the contacts 3_b, 4_b and fork mechanisms 3_c 4_c are dispensed with, the points 1_a, 2_a being directly connected to the points 8 and 7 respectively, and the circuits for the solenoids M₁ M₂ being completed through contacts 8_c 9_c 8_d and through contacts 11_c 10_c 11_d respectively. These contacts are associated as shown, with relays B₂ B₃, in such manner that when relay B₂ is energized, contact 1_d is opened and contacts 8_c 9_c closed, while when relay B₃ is energized, contact 9_d is opened and contacts 10_c 11_c closed. The relays B₂ B₃ also actuate each a further pair of contacts 4_c 5_c or 6_c 7_c, closing said contacts when the appropriate relay is energized. The output from the

5 valves V₁ V₂ is fed to a sensitive polarized relay B₁ which is biased to a desired degree by current flowing through an adjustable resistance R₁₀ in series with the relay winding. R₆₁, R₆₂ are adjustable resistances whereby the sensitivity of the relay B₁ may be adjusted. The tongue 12_c of the relay B₁ co-operates with contacts 13_c 14_c. As will be seen, when said relay is in its upper position, a battery E_{g3} applies negative potential to the grid of a valve V₃ through a circuit comprising armature 12_c, contact 14_c, contacts 4_c 5_c, resistance R₂₀ and battery E_{g1} (assuming relay B₂ to be in de-energized position) while when relay B₁ is in its lower position, potential is applied from the battery E_{g3} 10 to the grid of the valve V₄ through a circuit comprising armature 12_c, contact 13_c, contacts 6_c, 7_c, resistance R₄ and battery E_{g2} (assuming relay B₃ to be in de-energized position). The junction point of resistance R₂₀ and battery E_{g1} is 15 connected to the cathode of the valve V₃ through a resistance R₃ and a condenser K₁ in parallel, and similarly a resistance R₅ and a condenser K₂ are shunted across the grid circuit of the valve V₃. 20

25 The operation of this device is as follows:—

Suppose the armature 12_c to be in its upper position and contacts 4_c 5_c to be opened, and a charge to be in condenser K₁ sufficient to bias the grid of the valve V₃ negatively, so that the 30 anode current of valve V₃ is zero or very low. The condenser K₁ will gradually discharge through the associated resistance R₃, and when the negative potential applied to the grid of valve V₃ has fallen to a predetermined value, the 35 anode current of said valve will rise sufficiently to energize relay B₂, thus closing contacts 4_c 5_c and breaking the circuit of magnet M₂. The condenser K₁ now begins to charge again, applying a gradually increasing negative potential to 40 the grid of valve V₃, until the anode current of said valve falls to an extent sufficient to de-energize relay B₂, and opens contact 4_c 5_c, at the same time closing the circuit of magnet M₂. Thus magnet M₂ will be energized and deenergized successively during the periods that armature 12_c is against contact 14_c, the number of 45 movements of the armature of the relay B₂ per unit of time depending upon the value of the condenser K₁, the resistance R₃ and the other 50 constants of the circuits. Similarly, while relay armature 12_c is against contact 13_c, the magnet M₁ will be energized and de-energized successively. It will be noted that contacts 8_c 9_c of 55 relay B₂ are included in the circuit of magnet M₁, while contacts 10_c 11_c of relay B₃ are included in the circuit of magnet M₂, and that the two magnets M₁ M₂ are therefore prevented from being energized together. The relay B₁ is adjusted so that armature 12_c contacts with 60 one or other of its associated contacts when the current in the detector valves V₁ V₂ reaches a permissible maximum or a permissible minimum value.

Figure 4 of the accompanying drawings shows 65 a slight modification of the arrangement shown in Figure 3, the modification consisting in providing high speed relays B₄ B₅ arranged to be actuated by the relays B₂ B₃ instead of utilizing the latter relays directly. The contacts of the relays B₄ B₅ are indicated by the same references as those which indicate the corresponding contacts of the relays B₂ B₃ in Figure 3.

70 The operation of the apparatus illustrated in Figures 3 and 4 will be more readily understood 75

by reference to Figure 3A, which is a line diagram of the apparatus of Figures 3 and 4 and of the apparatus described in detail in the parent application referred to above. This line diagram 5 which is somewhat similar to the line diagram of Figure 1A in some respects differs therefrom as for example the thermionic relay TR is shown as being connected directly on the one hand to the detector separator output as shown more in 10 detail in Figures 3 and 4, and on the other hand to the input resistances of the detector separator through MR. The resistances R¹ and R² are controlled partly in accordance with amplitude 15 variations in the output of the detector separator and partly in accordance with the positions of the first and final movable contacts in the attenuation network which is shown as being connected to both the relay MR which is in turn connected to the input side of the detector separator.

It will be appreciated that the present invention, when applied to a radio receiver, secures a 20 step by step regulation of the low frequency output by a combined regulation of the input allowed into both the high frequency and low frequency amplifiers, without changing the characteristics of the said amplifiers.

In the parent specification is explained an arrangement whereby a carrier wave may be utilized 25 to obtain regulation of modulation side bands. Such utilization is, of course, possible with apparatus in accordance with the present invention. Further, in cases where a carrier or a carrier and one side band is or are suppressed, 30 it is possible to employ apparatus in accordance with either the present or the parent invention, by transmitting for the purpose of effecting regulation an additional modulation frequency lying outside the frequency band of signal modulations, 35 i. e. in the case of speech, by sending an additional modulation frequency lying outside the band, say, 500-2300 cycles. With such an arrangement 40 it is merely necessary to filter out the additional frequency by means of a high or low pass filter from the output of the telephone detector (in the 45 case of speech), rectify the said frequency and employ it for the control of the relays in the automatic current limiting and regulating device. Alternatively the additional frequency may lie 50 within the range of signaling frequencies, the same frequency in the signals being suppressed. For example, in the case of speech, the additional 55 frequency may be one of 1500 cycles, a filter, preferably of the Wheatstone bridge type, being inserted in the output from the detector to prevent impulses of 1500 cycles frequency being passed on to the low frequency amplifier. It is found that such suppression of a single frequency does not materially affect the intelligibility of speech.

I claim:

1. In radio apparatus, the combination of signal receiving means, amplifying means, detecting means associated with said amplifying means, low frequency amplifying means, signal amplitude regulating means interposed between said receiving means and said amplifying means, a second signal amplitude regulating means interposed between said detecting means and low frequency amplifying means, and means responsive to a current component obtained from said detecting means to control both of said amplitude regulating means.

2. In a radio receiver, high frequency signal receiving means, high frequency amplifying means, detecting means connected to said am-

plifying means, low frequency amplifying means, amplitude regulating means interposed between said high frequency means and said detecting means, signal amplitude regulating means interposed between said detecting means and said low frequency amplifier, means associated with said detector for separating a uni-directional component therefrom, means actuated by said uni-directional component and responsive to amplitude variations therein for controlling both 10 of said amplitude regulating means, and a third amplitude regulating means actuated in accordance with variations in amplitude of said uni-directional current and operatively interposed thereby between said detecting means and said 15 low frequency amplifying means when the amplitude of the signals in said high frequency amplifier reaches a predetermined value.

3. The method of receiving modulated high frequency energy which includes collecting modulated high frequency energy, amplifying the high frequency energy, rectifying the energy, amplifying the rectified alternating component of the rectified high frequency energy; and dissipating both the high frequency energy and its 20 rectified alternating component in accordance with variations in amplitude of the uni-directional component of the rectified high frequency energy.

4. In radio apparatus, the combination of 30 means for receiving high frequency signals, detecting means, signal amplitude regulating means connecting said detecting means to said receiving means, amplifying means associated with the output circuit of said detecting 35 means, means operated in accordance with variations in amplitude of a uni-directional component obtained from said detecting means for controlling said amplitude regulating means, a resistance network, and means actuated by said 40 uni-directional component for inserting said network between said detecting means and said amplifying means during the operation of said first named means.

5. An improvement in amplitude control means 45 comprising an automatic current limiting and regulating device inserted in a translating system to limit low frequency currents therein and automatic means controlled by the intensity of the current fed to said limiting and regulating device 50 for regulating the intensity of the current fed to said regulating device in a plurality of steps, said automatic means including switching devices and a pair of magnets adapted to drive said switching devices, means for generating electrical impulses 55 and means controlled by the intensity of the current fed to said automatic current limiting and regulating device for feeding the generated impulses to said magnets.

6. An apparatus as claimed in claim 5 in which the means for generating electrical impulses comprises a condenser and means for successively charging and discharging said condenser.

7. An arrangement as claimed in claim 5 in which the means for generating electrical impulses comprises a condenser and the means for successively charging said condenser including a plurality of thermionic impulse generators, one associated with each magnet and a polarized relay energized in dependence upon the signal input to 70 the automatic current limiting and regulating device.

8. A signaling system comprising, a device responsive to signal modulated carrier frequency energy, signal demodulating means connected 75

with said device, signal amplifying means connected with said demodulating means, a translating device connected with said signal amplifying means, and means for regulating the amplitude of the signal impressed on said translating means comprising, a device for selecting a direct current component from the output of said demodulating device, a step-by-step device interposed between said signal responsive device and said signal demodulating means for regulating the amplitude of the carrier wave impressed on said demodulating means, amplitude regulating means interposed between said demodulating means and said amplifier, and relays actuated by said selected direct current component for actuating said first and second named amplitude regulating devices.

9. The combination of a device for demodulating a signal modulated carrier wave and an amplifier connected with said demodulator, of a resistance network connected with the input of said demodulator to regulate the amplitude of the signal modulated carrier impressed thereon and a resistance network interposed between the output of said demodulator and the amplifier, of means for selecting a direct current component from the output of said demodulator, of thermionic means actuated by said direct current component to control the resistance network connected with the input of said demodulator, and automatic means for controlling the network between the demodulating device and said amplifier.

10. An improvement in amplitude control apparatus comprising, an automatic current limiting and regulating device inserted in a line to limit or regulate low frequency currents flowing therein, and automatic means controlled by the intensity of the input to said automatic current limiting and regulating device for regulating said input in a plurality of steps, said automatic means comprising, signal intensity reducing means, switching means for controlling said signal intensity reducing means, and a pair of magnets or solenoids adapted to drive said switching means in one of two opposite directions, whereby said automatic current limiting and regulating device produces its own amount of regulation of input strength, the steps all being such that the whole effective range is continuous and broken only by the steps of regulation effected by the

automatic current limiting and regulating device.

11. A signaling system comprising, a thermionic demodulator tube having its input electrodes connected with a source of signal modulated carrier waves by way of an incoming line terminated by a tapped resistance, an output circuit connected with said demodulator tube, and means for controlling the amount of resistance interposed between said incoming line and said thermionic demodulator tube comprising, a second thermionic tube device energized by direct current components selected from the output circuit of said first named thermionic tube, a step-by-step device adapted when actuated to increase or decrease the amount of resistance interposed between said incoming line and said detector, and a magnetic relay associated with said step-by-step actuating device and energized by said second named thermionic tube.

12. A signaling system comprising, a pair of thermionic demodulators having input and output electrodes, a circuit which may be energized by signal waves to be demodulated, said circuit including resistances, a plurality of contacts connected with points on said resistances, movable contact members connected with the input electrodes of said demodulators, said movable contacts and said contacts connected with points on said resistances being shaped so that a connection between said circuit and said input electrodes is completed at all times, an output circuit connected with said demodulators, and means for controlling the amount of resistance interposed between said first named circuit and the input electrodes of said thermionic demodulators comprising, an additional thermionic tube device having its input electrodes energized when direct current components appearing in the output circuits of said first named thermionic demodulators rise above or fall below predetermined values, a step by step device adapted when actuated to move said movable contact members over said fixed contacts to increase or decrease the amount of resistance interposed between said circuit and the input electrodes of said detector, and a magnetic relay for actuating said step by step device, said magnetic relay being energized by current controlled by energy in the output of said additional thermionic tube.

GASTON ADELIN MATHIEU. 50
